UNITED STATES PATENT OFFICE

148,538

DESIGN FOR A TIRE HOLDER

Andrew L. Henkel, Chicago, Ill.

Application April 9, 1945, Serial No. 118,925

Term of patent 7 years

(Cl. D90—18)

To all whom it may concern:

Be it known that I, Andrew L. Henkel, a citizen of the United States, residing at Chicago, Cook County, Illinois, have invented a new, original, and ornamental Design for a Tire Holder, of which the following is a specification, reference being had to the accompanying drawing, forming a part thereof.

Fig. 1 is a front perspective view of a tire holder showing my new design; and

Fig. 2 is a rear perspective view thereof.

I claim:

The ornamental design for a tire holder, substantially as shown.

ANDREW L. HENKEL.
